UNITED STATES PATENT OFFICE.

CHARLES A. HAMILTON, OF ANNISTON, ALABAMA, ASSIGNOR TO ALABAMA PIPE & FOUNDRY COMPANY, OF ANNISTON, ALABAMA, A CORPORATION OF ALABAMA.

DOUBLE-CORE ARBOR FOR PIPE-FITTINGS AND THE LIKE.

1,237,510.

Specification of Letters Patent. Patented Aug. 21, 1917.

Application filed December 14, 1916. Serial No. 136,985.

To all whom it may concern:

Be it known that I, CHARLES A. HAMILTON, a citizen of the United States of America, residing at Anniston, in the county of Calhoun and State of Alabama, have invented certain new and useful Improvements in Double-Core Arbors for Pipe-Fittings and the like, of which the following is a specification.

10 My invention relates to an improvement in core arbors adapted to form double cores for use in casting fittings in pairs.

The object of my invention is to improve the present foundry practice of molding 15 sanitary soil pipe fittings, T-fittings, Y-fittings or bends, half S-traps, cast iron service and valve boxes, and all like parts which are suitable for casting in pairs, and to this end I provide a double arbor con-

20 nected at each end in such manner as to brace the arbor and make it as rigid as possible, one of the end connections being removable as a preferred arrangement in order to permit the finished castings to be 25 stripped from the arbor.

By tying the two arbors together at each end I both facilitate and cheapen the cost of making and handling the cores, for two cores can be made at one time in one core 30 box with approximately the same labor cost required for one core and I make easy the carrying of the double cores to the molds and facilitate the shaking out of the fittings, all of which advantages are instru- 35 mental in reducing the cost of manufacture. Moreover, by tying the two arbors together I save space in the flasks, making it possible to increase the number of fitting molds per flask and to reduce the floor space necessary 40 for a given output.

Another advantage is that the arrangement of the molds for use with the double core can be such that only one gate is necessary to pour both molds, thus economizing 45 in metal and cutting the labor of pouring in half.

Another advantage of tying the two arbors together is that when the two sand cores are formed thereon and the whole

placed in the molds, the cores balance each other as to weight and the fixed and removable end connecting bars form handles as well as rigid core prints which make it impossible for the core to move out of position in the mold when metal is being poured, *i. e.*, 55 the double core is held positively and rigidly in its proper fixed position in the molds at all times.

My invention further comprises the novel details of construction and arrangements of parts which I have not attempted to illustrate or describe in the variety of embodiments of which my invention is capable but which in principle and in operation will be understood by those skilled in the art by 65 reference to the accompanying drawings which form a part of this specification, and in which:

Figure 1 illustrates in perspective view the drag rammed for receiving the double 70 cores, one of which is shown seated in the mold and the other of which is about to be placed in the mold.

Fig. 2 is a plan view of one form of the 75 double arbor.

Figs. 3 and 4 are detail views showing the parts of the arbor.

Fig. 5 is a partial perspective view of the cope.

Similar reference numerals refer to similar parts throughout the drawings.

I have illustrated my invention as adapted for forming double cores for use in a drag 1 in which is formed, in the manner well understood in the art, a plurality of duplex 85 or double molds 2 adapted to receive the double sand core. The core is made for use in casting pipe fittings known as "bends" and comprises the main body portions 3 and the head core 4 connecting the same and 90 forming the lateral branches of a pair of bends cast thereon. This core is formed over a double arbor comprising three main body sections 5, 6 and 7, the arbor sections 5 and 6 being similar straight arbors rigidly 95 connected at one end by an integral rigid cross bar 8 which has its under face reduced slightly between its ends where it is cast

jointed to the arbors 5 and 6. Its middle portion therefore will stand slightly above the level of its ends 9 and 10 which form spaced prints for the end of the double arbor. The arbors 5 and 6 are rigidly connected at their other ends when in use by the section arbor 7 which constitutes in effect a detachable cross bar for that end of the double arbor and has at its center a semi-circular disk 11 and at each end a thickened head provided with a downwardly tapering dove-tail lug 12. These lugs are adapted to fit in correspondingly shaped dove-tail downwardly tapering slots 13 in heads 13 formed on the detached ends of the arbors 5 and 6. In the particular type of arbor shown for a right angled bend fitting, the removable arbor 7 is set at right angles to the arbors 5 and 6, and it carries at its center an integral handle and print extension 14 which, as seen in Fig. 1, projects from the core and, with the rigid cross bar 8 at the other end, form handles in line with the center of gravity of the double core with respect of which the two cores are balanced and can be conveniently and expeditiously transported and placed in the molds. It will be noted that the mold is formed with a seat 15 for the print 14, which seat stands opposite the reduced intermediate portion of the bar 8 between the prints 9 and 10, which prints and said intermediate portion are received in appropriate seats 19 therefor formed in the drag. This causes the prints 9, 10 and 14 of adjacent cores to distribute the core weight uniformly across the sand in the drag and affords a surer and more reliable setting of the core.

In practice, the double arbor is assembled by fitting the end section 7 onto the main sections 5 and 6 and then the arbor as a whole is set up in a mold and the double sand core formed thereon in one operation in the manner well understood in the art. The operator then grasps the center of the cross bar 8 and the print 14 and lifts the core with ease and without any tendency of any part thereof to be strained or to give in any way so as to distort the core or get any part thereof out of line. The core is then set in the double mold formed in the drag, as shown in Fig. 1, a cope 17 having gates 18 to register with the double gate 16 in the drag is mounted on the drag, and the metal is poured through the gates and flows into the several double molds in the drag to form the casting. After the casting has been poured it is lifted out by the same convenient handle portions and is shaken out, after which the end arbor section 7 is removed and the arbor slipped from the casting.

It will be obvious that with slight modi-

fication the arbor can be designed for molding various styles of pipe fittings, traps, cast iron service or valve boxes, and in fact, any other type of casting which lends itself to being cast in pairs with the economies and advantages as above set forth.

In accordance with the provisions of the patent laws I have illustrated only one embodiment of my invention, but it will be understood that the same is capable of wide variation in design, size, shape and material, without departing from the essential principles forming the basis of my invention.

What I claim as new and desire to secure by Letters Patent, is:—

1. A double arbor for making castings in pairs, the arbor comprising connecting members at each end, at least one of which is detachable and each of which serves as a handle for transporting the finished core.

2. A core arbor for the manufacture of hollow castings in pairs comprising, in combination, two like body portions forming the main arbors, transverse cross connecting members which rigidly connect said main arbors and constitute both prints and handles therefor, and means to part the double arbor to remove it from the finished castings, substantially as described.

3. In an apparatus for molding castings in pairs, a mold having a double mold cavity and a single gate for pouring the same, of a core having a double core arbor rigidly connected at each end, said cross connections forming handles for the core with respect to which the weight of the arbor is balanced, substantially as described.

4. An arbor for molding castings in pairs comprising similar main body portions with rigid bracing cross connections for each end, one cross connection forming prints at its ends only and the other cross connection forming a print opposite the space between the prints at the other end of the arbor, and means to part the arbor to remove it from the finished castings, substantially as described.

5. In a molding apparatus for casting hollow articles in pairs, a cope, a drag comprising a series of duplex mold cavities, and double core arbors having cross connections at each end to rigidly brace them, said cross connections forming handles for the arbor and prints for the core, one handle being formed by a narrow projecting member and the other handle being formed by a cross bar reduced at the center of its under face opposite said narrow member and forming prints only at the unreduced ends thereof, substantially as described.

6. A double core arbor for casting in pairs hollow fittings having a lateral extension at one side thereof, said arbor comprising two

main arbor sections rigidly connected by an integral cross member at one end which forms a handle and connected at their outer ends by a detachable core arbor section, said latter section having projecting therefrom along the center line of the double arbor a narrow print which forms a handle, there

being prints provided at the other end of each main arbor portion, substantially as described.

10

In testimony whereof I affix my signature.

CHARLES A. HAMILTON.
